UNITED STATES PATENT OFFICE.

CHARLES KRES, OF CLEVELAND, OHIO, ASSIGNOR TO THE FORMAN BASSETT COMPANY, A CORPORATION OF OHIO.

DESIGN FOR SAFETY PAPER.

61,165.

Specification for Design.

Patented July 4, 1922.

Application filed February 11, 1921. Serial No. 444,800. Term of patent 14 years.

To all whom it may concern:

Be it known that I, CHARLES KRES, a citizen of the United States, and a resident of Cleveland, Ohio, have invented certain new, original, and ornamental Design for Safety Paper, of which the following is a specification, reference being had to the accompanying drawing.

The figure of the drawing shows a portion of safety paper embodying my new design.

I claim as my invention:

The ornamental design for safety paper surface, as shown.

CHARLES KRES.
